UNITED STATES PATENT OFFICE.

JOHN SHAW, SR., OF BAYONNE, NEW JERSEY.

DRAINAGE-TRAP.

SPECIFICATION forming part of Letters Patent No. 399,442, dated March 12, 1889.

Application filed September 24, 1888. Serial No. 286,194. (No model.)

To all whom it may concern:

Be it known that I, JOHN SHAW, Sr., of Bayonne, in the county of Hudson and State of New Jersey, have invented a new and Improved Drainage-Trap, of which the following is a full, clear, and exact description.

The object of the invention is to provide a new and improved drainage-trap, which is simple and durable in construction and very effective in operation, discharging the water of condensation automatically whenever a certain quantity has accumulated.

The invention consists of a float operating in a casing and controlling a piston connected with the outlet-valve.

The invention also consists in certain parts and details and combinations of the same, as will be fully described hereinafter, and then pointed out in the claims.

Reference is to be had to the accompanying drawings, forming a part of this specification, in which similar letters of reference indicate corresponding parts in all the figures.

Figure 1 is a sectional side elevation of the improvement. Fig. 2 is a transverse section of the same on the line *x x* of Fig. 1, and Fig. 3 is a sectional plan view of the same on the line *y y* of Fig. 1.

The improved drainage-trap is provided with a casing, A, having on one side a channel, B, connected at its upper end with an inlet-pipe, C, leading to the steam-supply. The channel B is connected with the interior of the casing A by an aperture, D, formed in the wall of the channel B a short distance below the inlet-pipe C. In the bottom of the channel B is formed another opening, E, also leading into the interior of the casing A near its bottom. Opposite the aperture E is placed a blow-off pipe, F, closed by a suitable valve in the usual manner until it is desirable to clean the casing A from sediment.

A short distance above the bottom of the casing A is formed an offset, A', in which opens the water-outlet pipe G, provided at its upper end with a valve-seat, G', in which fits a valve, H, opening inward and of any approved construction. The valve H is secured on a piston-rod, I, connected with the piston J, mounted to slide vertically in a cylinder,

K, supported on a bracket, L, fastened in the casing A.

On the cylinder K is formed a valve-chest, N, in which operates a valve, O, adapted to open and close the ports *a* and *b*, leading to the top and bottom of the cylinder K, respectively. The valve O also controls the outlet-port *c*, passing through the bracket L to the outside of the casing. The valve O is mounted to turn in the valve-chest N, and is provided with a valve-stem, O', carrying an arm, P, pivotally connected by a link, Q, with the short arm of a bell-crank lever, R, fulcrumed on the bracket L and pivotally connected with a rod, S, provided with two collars, S' and S'', between which travels a float, T, guided in the vertical guide-rods U, secured to the bottom of the casing A. The float T is provided in its center with a pipe, T', through which passes the rod S, as is plainly shown in Fig. 1. 70

The operation is as follows: The steam entering through the inlet-pipe C passes into the channel B and through the openings D and E into the interior of the casing A. The water of condensation accumulates in the casing A, finally closing the opening E, so that all the steam passes through the aperture D. The float T rises with the water in the casing A until it strikes against the collar S' on the rod S. When the water now accumulates 75 further in the casing A, the said float T presses against the collar S', so that the rod S is moved upward, the bell-crank lever R is turned, and the valve O is shifted, uncovering the inlet-port *a*, whereby steam passes from the casing 80 A into the bottom of the cylinder K and acts against the under side of the piston J, whereby the latter is raised and the valve H is unseated from its seat G'. The accumulated water of condensation now flows out through 85 the pipe G until it reaches the level of the offset A'. The float T naturally sinks with the water and operates on the collar S'' shortly before the water reaches the level of the seat G' in the offset A'. The rod S is thus moved 90 downward, the bell-crank lever R is swung, and the valve O is turned so as to uncover the other inlet-port, *b*, whereby steam passes to the top of the cylinder K and forces the piston J downward, thereby again seating the 95 100

valve H on its seat G'. The pipe G is thus closed and the water of condensation can again accumulate in the casing A. The exhaust from the cylinder K always takes place 5 through the outlet-port c in the usual manner.

The valve-seat G' of the pipe G is located somewhat above the bottom of the casing A to prevent the sediment from passing into the pipe G. The sediment settles in the bottom 10 of the casing and can be removed by opening the valve in the blow-out pipe F in the usual manner.

Thus it will be seen that the drainage-trap automatically discharges the water of condensation whenever a sufficient quantity has 15 accumulated.

Having thus described my invention, what I claim as new, and desire to secure by Letters Patent, is—

- 20 1. In a drainage-trap, the combination, with a cylinder provided with a valve-chest and inlet and outlet ports, of a piston held to travel in the said cylinder, an outlet-valve supported on the said piston, a valve held to swing in the said valve-chest and operating over the said ports, and a float operating the said valve, substantially as shown and described.
- 25 2. In a drainage-trap, the combination, with a casing provided with an inlet and an outlet, of a valve seated in the said outlet, a piston supporting the said valve, a cylinder containing said piston and provided with a valve-chest and inlet and outlet ports, a valve held 30 in the said valve-chest and operating over the said ports, a rod connected with the said valve and provided with collars, and a float
- 35

traveling on the said rod between the said collars, substantially as shown and described.

3. The combination, with a casing provided 40 with an inlet and an outlet pipe, of a valve seated in the said outlet-pipe and opening inward in the said casing, a piston-rod supporting said valve, a piston connected with the said piston-rod, a cylinder containing said 45 piston and provided with inlet and outlet ports, and also with a valve-chest, a valve held to turn in the said valve-chest and operating over the said ports, a bell-crank lever connected with the said valve, a rod pivotally 50 connected with the said bell-crank lever and provided with collars, and a float held to travel on the said rod between the said collars, substantially as shown and described.

4. The combination, with a casing provided 55 with an inlet and an outlet pipe, of a valve seated in the said outlet-pipe and opening inward in the casing, a piston-rod supporting said valve, a piston connected with the said piston-rod, a cylinder containing said piston and 60 provided with inlet and outlet ports and also with a valve-chest, a valve held to turn in the said valve-chest and operating over the said ports, a bell-crank lever connected with the said valve, a rod pivotally connected with the 65 said bell-crank lever and provided with collars, and a float held to travel on the said rod between the said collars, and guide-rods held in the said casing for guiding said float, substantially as shown and described.
